VACUUM CONTAINER

Filed Dec. 20, 1928

UNITED STATES PATENT OFFICE

WARREN M. MYERS, OF SAGINAW, MICHIGAN

VACUUM CONTAINER.

Application filed December 20, 1928. Serial No. 327,365.

This invention relates to vacuum bottles or containers and the general object of the invention is to provide a thermos bottle or container within which liquids may be kept in a heated or cold condition and from which they may be drawn off without removing any cap or closure, thus eliminating the loss of temperature caused by opening the interior of the container to the outside air.

10 A further object is to provide a structure of this character with a tap or faucet and provide means whereby air may be allowed to flow into the interior of the container to make up for the displacement of liquid due 15 to the drawing off of some of the contents of the container.

A further object is to provide a device of this character wherein the lower end of the container is provided with a draw-off faucet 20 and the top of the container is provided with an air inlet valve, thus permitting the faucet to be turned on and then the valve opened so that the pressure will cause the discharge 25 of liquid through the faucet.

When it is desired to stop the flow of liquid the air inlet valve may be closed, thus stopping the outflow of liquid and then when the outflow has stopped, the faucet will be closed.

Other objects will appear in the course of 30 the following description.

My invention is illustrated in the accompanying drawings, wherein:—

Figure 1 is a vertical sectional view of a vacuum container constructed in accordance 35 with my invention;

Figure 2 is a top plan view thereof;

Figure 3 is a section on the line 3—3 of Figure 1.

Referring to the drawings, 10 designates 40 the outer wall of a vacuum jar or container and 11 the inner wall thereof. These walls are illustrated as being continuous or integrally connected but I do not wish to be limited to this. The two walls 10 and 11 merge 45 into a base 12 which is hollow to continue the vacuum chamber 13 in the base, this chamber being normally closed by a screw plug 14 or like contrivance.

The exterior of the container is formed 50 with outwardly projecting flanges 15 between

which a sheet of nickel or other metal may be placed or between which insulating material may be wrapped. The outer wall 10 is provided with the ears 16 apertured for engagement with a bail. The bottom 12 is 55 formed with a central port 17 which extends laterally outward and discharges into the bore of a faucet 18 of any usual or suitable character, such as are commonly found on coffee urns or the like.

The upper end of the container is formed with a central passage 19 which, outward of the chamber defined by the wall 11, is enlarged and interiorly screw-threaded at 20. Engaged with these screw-threads is an exteriorly screw-threaded closure plug 21 which has a central bore interiorly screw-threaded and disposed within this central bore is a sleeve 22 in turn having a central bore to receive a sleeve 23 having a valve seat 24 at its lower end. Bearing against the under face of this valve seat is a valve 25 having a stem 26 provided with a head 27 at its upper end and a coil spring 28 bearing against this head and bearing against the seat 24 urges 70 the valve upward against its seat.

When it is desired to open the valve, the head 27 is depressed by the finger, whereupon the valve will open to permit the entrance of air. This head 27 is normally disposed below the upper ends of the sleeves 22 and 23 but in order to prevent any possible chance of the valves being depressed by anything resting thereon, I form the flange 29 of the closure or plug 21 with the outwardly 80 projecting circumferential lugs 30.

The inner wall 11 at its junction with the bore 19 is formed with a packing seat for the reception of an annular packing ring 31. Resting upon this packing ring and pressed firmly thereagainst by the closure 21 is the head 32 of a tube 33 which extends downward into the interior of the vessel and discharges adjacent the outlet duct 17. This permits the pressure of air to bear against the upper surface of the liquid column in the tube and causes the discharge of the contents of the vessel when the faucet 18 is opened.

Where the vessel is to be used for holding coffee, tea, or other liquids in which there may 100

be sediment needing to be strained off, I provide a strainer bag 34 which may be made of metal or of textile material, the upper end of this strainer bag being mounted upon a hoop 35 and the lower end of this strainer being 5 connected to a ring 36 which fits closely around the tube 33. Thus, when it is desired to fill the interior of the vessel with such liquid as coffee or tea, the closure 21 is removed, the head 32 is lifted together with the pipe 33 until the head 32 has been lifted sufficiently to permit the flow of liquid into the 10 upper end of the strainer. The liquid is then poured in and the strainer strains off tea 15 grounds, coffee grounds or if the beverage is say lemonade, the seeds, which might otherwise pass into the interior of the container. When the container has been filled to the proper degree, the tube 33 is forced inward 20 until the head rests upon the seat, then the closure is screwed home and the parts are in position for operation.

When it is desired to use the device, the faucet 18 is first opened, but because no air 25 is allowed to enter the interior of the vessel, the liquid will not flow out of the faucet. Therefore, it is necessary to then press on the button or head 27 which opens the valve to admit the air. When the glass or cup is 30 nearly full the valve 25 is allowed to close but the faucet is left open until the liquid stops flowing. Then the faucet is closed. By this operation, only a minimum change in 35 temperature can possibly occur inasmuch as only a minimum amount of air enters into the interior of the vessel sufficiently to make up for the liquid displaced. It will be seen that liquid can be drawn from this vessel without removing the closure 21, thus allowing 40 only the amount of air needed to enter. The temperature will thus be changed by only a minimum amount. It will be understood that the faucet remains open until the liquid stops its flow and then the faucet is closed.

45 While in the drawings I have illustrated a principle of my invention, I do not wish to be limited to it as this may be varied in many ways without departing from the spirit of the invention as defined in the appended 50 claims. While I have illustrated the head 32 and the closure 21 as being made in two separate sections, I do not wish to be limited to this as the closure 21 and the head 32 might be made in one piece so that when the closure 55 is lifted the pipe 33 will come out with the closure, thus permitting either the entire removal of the pipe 33 from within the bag 34 or permitting the closure 21 to be lifted sufficiently far to allow liquid to be poured into 60 the vessel and pass downward within the bag 34.

Fluid will be at the same level inside the pipe 33 as exteriorly of the pipe and will hold enough liquid so that there will not be 65 so much disturbance in analyzing and inas-

much as the lower end of the vent pipe is close to the bottom of the vessel, the inlet of air will occur immediately over the opening 17. The parts 23 and 29 are separate so that the valve 25 may be taken out without removing 70 the pipe 33.

I claim:—

1. A dispensing container of the character described having an outlet faucet or tap at its lower end, a removable closure for the 75 upper end of the container which when removed permits liquid to be poured into the container and which when closed permits the inlet of air thereinto, an air valve disposed in said closure and yieldingly urged to a closed position, the air valve having a means whereby it may be manually shifted, the closure having upwardly projecting bosses extending beyond the upper end of the air valve to prevent the accidental operation of the valve. 80

2. A dispensing vessel of the character described having an outlet port in its bottom and a faucet with which the port communicates, the upper end of the vessel being formed with a central opening, a closure having 85 screw-threaded engagement with the opening and having a central normally closed, manually depressible air inlet valve, the wall of said opening being formed with a seat below the valve, and an air conducting pipe having 90 a head resting upon said seat, the lower end of the closure bearing against said head on the air pipe and holding it to its seat, the pipe terminating short of the bottom of the vessel. 95

3. A dispensing vessel of the character described having double walls, the space between the walls being evacuated of air, the lower end of the vessel having an outlet duct and a faucet communicating therewith, the upper end of the vessel having a central aperture, the inner wall of the vessel projecting inward to define an annular seat, a closure having screw-threaded engagement with the wall of said aperture but larger in diameter 100 than the seat, the closure being provided with a manually depressible, normally closed valve whereby air may be admitted through said closure, and a pipe disposed below the valve 105 and supported upon said seat and extending downward into the interior of the vessel but spaced from the bottom thereof, the closure at its upper end having an annular flange extending over the upper end of the vessel, the flange being provided with upwardly 110 projecting bosses extending above the upper end of the valve stem to prevent the accidental operation of the valve. 115

4. A dispensing vessel of the character described having an outlet port in its bottom and a faucet with which the port communicates, the upper end of the vessel being formed with a central opening, a closure having 120 screw-threaded engagement with the opening and having a central normally closed, 125

manually depressible air inlet valve, the wall of said opening being formed with a seat below the valve, an air conducting pipe having a head resting upon said seat, the pipe terminating short of the bottom of the vessel, and a strainer surrounding said pipe and at its upper end having a hoop engageable upon said seat, the lower end of the strainer having a ring slidingly but closely engaging the pipe.

5 5. A dispensing container of the character described having a central chamber and an outer, evacuated jacket, the inner and outer walls of the jacket extending upward above the chamber and the inner wall being interiorly screw-threaded, the lower portion of the container having a duct extending from the center of the container radially outward and carrying a faucet, a closure plug having 10 screw-threaded engagement with the inner wall of the jacket at the upper end of the container and carrying an air valve urged to its seat by a spring but manually openable, and a head disposed below the plug and held 15 in place thereby and carrying an air pipe extending downward toward and approximately in line with the discharge opening at the lower end of the container, the air pipe being removable when the plug is removed 20 and being held rigidly in place by the plug.

25 In testimony whereof I hereunto affix my signature.

WARREN M. MYERS.
